HOLDER FOR MOPS AND OTHER DEVICES

Ira Hertzberg, Yonkers, N. Y., assignor to H. Hertzberg & Son, Inc., New York, N. Y., a corporation of New York

Application May 5, 1949, Serial No. 91,480

3 Claims. (Cl. 15—147)

1

My invention relates to a new and improved assembly of a clip and a helical spring.

One object of my invention is to provide an improvement upon the device illustrated in U. S. Patent No. 2,413,564, dated December 31, 1946.

The device of the present invention is used in the manner disclosed in said U. S. Patent No. 2,413,564.

According to this invention, I provide a clip which has two longitudinal legs, of different respective lengths. Each leg has a lateral extension at its inner end. These lateral extensions extend laterally oppositely from said legs. Each of said lateral extensions has a hook-shaped end-flange, which interfits slidably and turnably with the same coil of the helical spring or with different coils of the helical spring. The free edges of said end-flanges are located inwardly of the outer longitudinal wall of the helical spring. The clip is thus assembled more easily and securely with the helical spring by a screw-like rotary motion, and the free edges of the end-flanges cannot cut the user or a garment of the user.

Numerous additional objects and advantages of my invention are stated in the annexed description and drawings, which illustrate a preferred embodiment thereof.

Fig. 1 is an elevation of the assembly, prior to the time that the clip is moved to final clamping position. A part of the helical spring is shown in vertical section.

Fig. 2 is a vertical axial section on the line 2—2 of Fig. 1. A part of the helical spring is shown in elevation.

Fig. 3 is a top plan view of Fig. 1.

Fig. 4 is a perspective view of the clip.

The clip 2 is made of metal or other suitable material. Said clip 2 is preferably made from a single flat metal blank, which can be shaped by usual stamping and bending operations. Said clip 2 may be rigid or resilient. It has the normal shape shown in Fig. 4.

At its outer end, clip 2 has a transverse end-member 5, which has the shape of a split cylinder, which has separated transverse edges 5a. Said clip 2 has longitudinal and planar legs L, which are parallel to each other and parallel to the straight longitudinal axis of helical spring 6.

Said legs L have outer end-portions 4a and 3a which are transversely tapered, so that their wide edges are integral with edges 5a of end-member 5. Said legs L have main body-portions 4 and 3 which are rectangular.

The inner ends of said legs L have integral

2

lateral extensions 8 and 7 which extend in opposed lateral directions.

These lateral extensions 8 and 7 have respective hook-shaped end-flanges 8a and 7a, which have respective inner end-walls 8b and 7b.

The spring 6 is a helical spring, which normally has a straight longitudinal axis. The coils of spring 6 may normally abut each other, or said coils may be normally spaced longitudinally, 10 when the spring 6 is free from any flexing or distorting force.

If the coils of spring 6 normally abut each other, the end-coil of spring 6, which is shown at the top of spring 6 in Figs. 1 and 2, may be 15 spaced longitudinally from the next adjacent coil of spring 6.

In this embodiment, the longitudinal cross-section of the coils of spring 6 is circular, and said spring 6 is of uniform diameter.

The concave inner faces of end-flanges 8a and 7a turnably and slidably interfit with and abut respective parts of a coil or coils of spring 6, so that clip 2 can be assembled with spring 6, or clip 2 may be removed from spring 6, by 25 a rotary screwing or rotary unscrewing movement.

In this embodiment, each lateral surface element of the inner faces of end-flanges 8a and 7a is therefore a circular concave arc.

The walls of the end-flanges 8a and 7a are preferably of uniform thickness, so that the outer surfaces of said end-flanges 8a and 7a have lateral convex surface elements which are circular convex arcs. The walls of end-flanges 8a and 7a preferably have the same thickness as lateral extensions 8 and 7.

The reference letter E designates the junction lines between the lateral extensions 8 and 7 and their respective end-flanges 8a and 7a.

The extensions 8 and 7 are preferably originally formed or shaped relative to legs L, prior to forming or shaping the end-flanges 8 and 7. When thus originally formed or shaped, each lateral extension 8 and 7 has surplus material 45 for subsequently forming the end-flanges 8a and 7a.

When lateral extensions 8 and 7 are shaped prior to forming the end-flanges 8a and 7a, said junction lines E preferably follow the desired helical contour. When the surplus material is then bent inwardly along junction lines E, to form end-flanges 8a and 7a, each said end-flange 8a and 7a has the desired part-helical shape.

As shown in Fig. 3, the lateral extensions 8 and 7 are diametrically laterally opposed, so that

their end-flanges 8a and 7a are also diametrically opposed.

Each end-flange 8a and 7a turnably and slidably engages substantially one-fourth of the circumference of a coil of helical spring 6.

In using this specific embodiment, the end-flanges 8a and 7a are engaged with one end of spring 6. The cross-bar 1 is extended through the hollow end-member 5. The clip 2 is turned relative to spring 6, until cross-bar 1 is clamped between end-member 5 and the respective end of spring 6.

As shown in Fig. 2, the thickness of inner end-walls 8b and 7b is preferably greater than the normal longitudinal spacing of the coils of spring 6. Hence, when clip 2 is assembled with spring 6, said spring 6 is extended at inner end-walls 8b and 7b and each inner end-wall 8b and 7b is clamped and frictionally held between two adjacent coils of spring 6.

The spring 6 may also thus frictionally clamp the lateral extensions 8 and 7.

Each junction line E has the shape of a part of a helix which has the same pitch as spring 6, so that each junction line E has the same contour as the coils of spring 6.

I have disclosed a preferred embodiment of my invention, but numerous changes and omissions and additions can be made without departing from its scope.

I claim:

1. A holding device, said device comprising a clip which has legs which are spaced from each other, said legs being connected to each other at the end of said clip, a helical spring assembled with said clip, each of said legs extending within the interior of said spring and having a first lateral offset which is located between adjacent first and second turns of said spring and which frictionally engages said respective adjacent turns of said spring and which has substantially the same pitch as said spring, each of said first lateral offsets having an extension which is external to said spring and which is substantially parallel to the axis of said spring and which has substantially the same pitch as said spring and which has an inner convex wall which is adapted slidably to receive said second turn of said spring and which is directed away from the end of said clip, each of said extensions having a second lateral offset which is located between said second turn of said spring and an adjacent third turn of said spring and which frictionally engages said second and third turns of said spring and which has substantially the same pitch as said spring.

2. A holding device, said device comprising a clip which has legs spaced from each other and connected to each other at the end of said clip, a helical spring assembled with said clip, the legs of said clip extending partially within the central

hollow interior of said helical spring, said legs having respective lateral offsets which project in diametrically opposite directions, between adjacent turns of said spring, said lateral offsets having sufficient thickness to be frictionally engaged and compressed between the respective adjacent turns of said spring, each of said lateral offsets having an arcuate end extension located exteriorly of said spring and embracing a portion of the outer periphery of one of the adjacent spring turns, the free end of each said extension extending between said embraced spring turn and the next adjacent turn and being compressed therebetween, said extensions having substantially the same pitch as said spring and being slidable around the outer periphery of said spring, whereby said legs may be moved longitudinally through the interior of said spring when said clip is rotated relative to said spring.

20 3. A holding device, said device comprising a clip which has legs spaced from each other and connected to each other at the end of said clip, a helical spring assembled with said clip, the legs of said clip being connected at one end and being free at their other end, said legs extending within the central hollow interior of said helical spring and being axially aligned with said spring, each of said legs having a terminal lateral offset, said offsets extending substantially perpendicularly of said legs in opposite directions and between adjacent turns of said spring, said offsets having sufficient thickness to be compressed between the respective adjacent turns of said spring, each of said offsets having an arcuate end extension located exteriorly of said spring and embracing a portion of the outer periphery of one of the respective adjacent spring turns, the free ends of each said extension extending between said embraced spring turn and the next adjacent turn and being compressed therebetween, said extensions having substantially the same pitch as said spring and being slidable around the outer periphery of said spring, whereby said legs may be moved axially through the interior of said spring when said clip is rotated relative to said spring.

IRA HERTZBERG.
